INVENTOR

Thomas Reno
By C. C. Leggett,

Attorney

UNITED STATES PATENT OFFICE.

THOMAS RENO, OF DETROIT, MICHIGAN.

BENCH-VISE.

SPECIFICATION forming part of Letters Patent No. 267,986, dated November 21, 1882.

Application filed October 10, 1882. (No model.)

To all whom it may concern:

Be it known that I, THOMAS RENO, of Detroit, county of Wayne, State of Michigan, have invented a new and useful Improvement 5 in Bench-Vises; and I declare the following to be a full, clear, and exact description of the same, such as will enable others skilled in the art to which it pertains to make and use it, reference being had to the accompanying drawings, which form a part of this specification.

My invention consists in the combinations of devices and appliances hereinafter specified, and more particularly pointed out in the claims.

In the drawings, Figure 1 is a side elevation 15 of an apparatus embodying my invention. Fig. 2 is a rear elevation. Fig. 3 is a separate view of one of the parts.

The object of my invention is to provide novel means whereby the jaws of a vise can 20 be quickly adjusted independently of the usual adjusting-screw.

In carrying out my invention, as shown in the drawings, A and A' represent the jaws.

B is any suitable operating-screw, passing 25 through them, provided with the handle or lever B'.

C is the lower slide-bar, rigidly secured in the jaw A', and passing through a mortise in the jaw A, said mortise preferably provided 30 with a pulley, a, beneath the slide-bar. Said slide-bar is also preferably provided with a groove, c, adapted to receive a chain.

D is a chain or cable of suitable length, secured to the end of the slide-bar, and passing 35 over pulleys a' and a² through the jaw A, and secured to the jaw A'.

E and E' represent the two portions of a divided nut or collar, rigidly secured upon the arms F and F'. Said arms are pivoted at one 40 end to the jaw A or to an intervening plate secured to said jaw.

H is a disk provided with a lever, H', and pivoted to the jaw A or to a plate on the jaw. Said disk is connected with the ends of the arms F and F' by means of the connecting-bars h and h'. These bars are secured eccentrically to the disk, the construction being

such that by raising and lowering the lever H' the arms F and F' are opened and closed, and consequently the two parts of the nut E and E'. 50 By this means the divided nut may be easily adjusted upon the threads of the screw B, or disengaged therefrom, as may be desired.

By securing the chain D to the jaw A' by means of a staple and nut, as shown at d, it is 55 evident that the chain may be tightened, if desired.

A vise so constructed may be made either of wood or metal, or of wood faced with metal, as may be preferred. Its operation will now 60 be understood. When it is desired to adjust the jaws, by rotating the disk H in the proper direction the nut or collar E E' is opened, allowing the jaw A to be moved freely back and forth upon the screw B to any desired distance. Then by rotating said disk in the opposite direction the collar is engaged upon the screw, when by the handle B' the jaws may 65 be tightened as required. It will be seen that when the jaw A is moved back or forth the 70 chain D will pass over the pulleys a' and a², and the two jaws will be kept parallel thereby.

What I claim is—

1. In a bench-vise, the combination, with the jaws and operating-screw, of the pivoted arms 75 F and F', provided with a divided collar or nut, E E', adapted to engage said screw, and means for opening and closing said arms, substantially as and for the purpose described.

2. The arms F and F', provided with the divided nut or collar E E', adapted to engage the operating-screw of a vise, and means for opening and closing said arms, the construction being such that the divided nut or collar may be closed upon or disengaged from said 85 screw, as may be desired, substantially as and for the purpose described.

In testimony whereof I sign this specification in the presence of two witnesses.

THOMAS RENO.
